JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed February 15, 1923. Serial No. 619,087.

This invention relates to typewriting machines, especially those known as "fan-fold" or "continuous billing" machines in which there are typed superimposed packs 5 or webs of work-sheets or plies, the latter being sometimes loose or separate from one another.

According to this invention, two packs or webs, one of which consists of two work-sheets or plies having a short form printed thereon, and the other of which consists of two work-sheets or plies having a long form printed thereon, may be fed through the machine, etc., in such a manner that the 15 pack having the shorter printed forms will be next to the platen of the typewriter, and the pack or web bearing the longer printed form will be away from the platen; whereby, part, but not all, of the matter typed on 20 the pack or web bearing the long printed forms will be transferred, by means of suitable carbon-sheets interleaved between the work-sheets or plies, to the pack or web bearing the short printed forms; and 25 whereby the leading edges of the two packs or webs may be so gaged at the conclusion of the typing operation that the work-sheets or plies may be torn off in unequal lengths.

30 For the purpose of illustration, it may be assumed that in practice the work-sheets or plies of the pack or web nearest the platen have a short label form printed thereon, and that the work-sheets or plies of the 35 pack or web away from the platen bear a long printed invoice form, and that it may be found desirable to transfer to the pack or web bearing the short label form only the matter that is to be typed on the heading of the long invoice form printed on the other pack or web.

To accomplish this, the work-sheets or plies of both packs or webs, together with the interleaved carbons which are held by 45 a suitable carbon-withdrawal mechanism, are drawn through the machine and around the platen. The leading edges of all of the work-sheets or plies of both packs are then placed in registration and the platen lowered to engage with the feed-rolls.

The matter to be first written, which may be a name and address, is now typed by the operator on the heading of the long invoice form printed on the top pack or web,

and is transferred by the carbons to the 55 short label form printed on the pack or web nearest the platen.

The operator is now ready to line-space and type on the body of the long invoice form, but it is obvious that if both packs 60 or webs are fed through the machine together, as is desirable, the body of the long invoice form will be superimposed over the second short label form that is printed on the work-sheets or plies of the lower 65 pack or web, and that the matter to be written on the body of the long invoice form will be transferred by the carbons to this second short label form. This is prevented by inserting shields or blind sheets 70 underneath the printing surfaces of those carbons which are superimposed over such work-sheets or plies as may bear the short label forms in such a manner as to render ineffective all of the printing surfaces except those of the extreme ends of the carbons which cover the first printed label forms. The shields or blind sheets are suitably fastened, together with the carbons, to the carbon-withdrawal mechanism. 75

At the conclusion of the typing operation, and when the body of the longer invoice form has been filled in, it is desirable that the operator so withdraw the leading edges of both packs or webs from the machine that the registration marks, which indicate what are to be the leading edges of all the work-sheets or plies for the second printed forms, will be presented in registration to be cut by a knife which is placed 85 in the machine for that purpose. This is accomplished by back-spacing or reversely feeding the combined packs or webs; releasing the platen by lifting it up and away from the feed-rolls; withdrawing the carbons and shields or blind sheets; and again advancing the packs or webs, this time with the fingers, until the present leading edge of the pack or web nearest the platen touches a lower leading-edge gage and the present 90 leading edge of the pack or web farthest from the platen touches an upper leading-edge gage, both of which gages are clamped or fastened on a gage-carrying bar 95 or guide which projects rearwardly and upwardly from the paper-table of the machine when that table is in its normal position.

100

105

The means for protecting the second short printed form from receiving the impression of the matter typed on the body of the first long printed form, and the means by 5 which the ends of the two packs or webs are gaged for length before the cutting operation is performed by the operator, will be more clearly described hereinafter.

It will be understood, however, that the 10 packs or webs may each contain any suitable number of work-sheets or plies, which may bear any suitable printed forms of various lengths in different ratio to one another than those shown herein.

15 Other features and advantages will hereinafter appear.

In the accompanying drawings,

Figure 1 is a diagrammatic view which shows the position of both packs or webs of 20 work-sheets or plies, together with their interleaved carbons and shields, with relation to the platen and gage-carrying bar at the conclusion of the typing operation.

Figure 2 is a diagrammatic view similar 25 to Figure 1, except that the packs or webs have been back-spaced or reversely fed.

Figure 3 is a diagrammatic view similar to Figure 2, except that the guide-carrying bar has been brought forward and downward and the platen raised to release it from the feed-rolls.

Figure 4 is a diagrammatic view similar to Figure 3, except that both packs or webs have been withdrawn by the fingers until 35 the leading edge of the pack or web nearest the platen has engaged the lower leading-edge gage.

Figure 5 is a partial, sectional view of the 40 machine with the platen and guide-carrying bar in similar position to that shown in the diagrammatic view, Figure 4. The pack or web nearest the platen has been fastened to the lower leading-edge gage by means of a spring clamp arrangement, and the other 45 pack or web has been further withdrawn to engage the upper leading-edge gage.

Figure 6 is a diagrammatic view similar to Figures 1 and 2, except that the packs or webs have been gaged for length and are 50 now ready to be cut off by the knife.

Figure 7 is a plan view of the top of the lower leading-edge gage, and shows the detail of the clamping mechanism.

Figure 8 is a view of one of the work-sheets or plies bearing the short printed 55 forms.

Figure 9 is a view of one of the work-sheets or plies bearing the long printed forms, and shows a depth of heading indicated on the forms to correspond with the 60 length of the short forms.

Figure 10 is a view of a carbon-sheet rendered ineffective for most of its length by a shield or blind sheet.

65 Figure 11 is a view of a modified carbon-

sheet made to have a printing surface only at its extreme end.

As is usual in the Underwood "fan-fold" or "continuous billing" machine, a platen 12 is supported by means of an axle 13, which is journaled in two end members 14 of a swing-frame 15. Ears 14^a projecting from the end members 14 are journaled on a shaft 16 about which the swing-frame 15 oscillates. The shaft 16 is journaled in a main 70 platen-frame 17, which also supports the forward end of a sub-frame 18 on which is 75 slidably mounted a carbon-withdrawal mechanism 19.

The platen 12 is actuated by having the 80 motion, that is imparted to the platen-rotating handle, transferred by means of a spur-gear 20, fastened to a platen-rotating handle shaft 21, through a spur-pinion 22, 85 loosely mounted on the shaft 16, to a spur-gear 23, fastened to the platen-axle 13. The platen 12 is held against feed-rolls 24 and 25 by the usual means of a pivoted hook which, however, is not shown in the drawings.

The end members 14 of the swing-frame 15 also form a support for a paper-table 26, which has suitably fastened thereon a gage-carrying or supporting bar 27, which carries a lower leading-edge gage 28 and an 90 upper leading-edge gage 29.

A pack or web 30, made up of the work-sheets or plies 30^a, is first interleaved with a carbon 31, which is rendered ineffective for 100 part of its length by a shield 31^a, which is fastened to the carbon-withdrawal mechanism 19, together with the carbon 31. An additional carbon 31, also rendered ineffective by a shield 31^a, is placed over the top work-sheet or ply of the pack or web 30. A pack or web 32, made up of work-sheets or plies 32^a, is interleaved with a carbon 33, and then placed on top of the pack or web 30. The work-sheets or plies 30^a of the pack or web 30 have printed thereon a short form, the length of which is indicated by a dividing line 34 in Figure 8. The work-sheets or plies 32^a of the pack or web 32 have printed thereon a long form, the length of which is indicated by a dividing line 35, in 110 Figure 9, and which has an upper margin or heading indicated in the same figure by a dotted line 36.

115 It will be observed that when the pack or web 32 is placed over the pack or web 30, the first long forms printed on the work-sheets or plies 32^a will be superimposed over both the first and second short forms printed on the work-sheets or plies 30^a, but that the shields 31^a will protect the second short 120 form printed on the work-sheets or plies 30^a from receiving impressions, through the carbons 31, of that matter typed on the body of the long forms printed on the work-sheets or plies 32^a, and that this second short form will 125 130

be left blank. If it is found more desirable to dispense with the shields 31^a, a carbon-sheet, such as is shown in Figure 11, having a blank body portion 37 and a sensitive end portion 38, may be used instead, in which case the blank body portion 37 will serve the same purpose as the shields 31^a in protecting the second short form printed on the work-sheets or plies 30^a.

10 The pack or webs 30 and 32, having been suitably arranged with their leading edges in registration, both are drawn through the machine together over the feed-rolls 24 and 25, and under and around the raised platen 12 until the leading edges are far enough past the typing line to receive the first line of matter. The platen 12 is lowered to its normal position in engagement with the feed-rolls 24 and 25, and the typing of matter on the packs or webs begun. After the matter that is intended for both the heading of the first long form printed on the work-sheets or plies 32^a and the body of the first short form printed on the work-sheets or plies 30^a has been typed, the operator disregards the second short form printed on the work-sheets or plies 30^a, because they are being protected from impressions from the carbons 31 by the shields 31^a, and continues to line-space or advance both packs or webs together and to type the balance of the matter intended for the body of the first long form printed on the work-sheets of plies 32^a.

35 At the conclusion of the typing operation it will usually be found that the leading edge of the pack or web 30 which bears the short printed forms has passed beyond the lower leading-edge gage 28 on the gage-carrying bar 27, as illustrated in Figure 1. Both packs or webs are back-spaced or reversely fed until they are in the position shown in Figure 2. The platen 12 is then raised away from the feed-rolls 24 and 25, by releasing the hook and oscillating the spring-frame 15 upwardly and forwardly about the shaft 16, until it assumes the relative position shown in Figure 3.

50 The leading edges of both packs or webs are now grasped by the operator in such a way that the pack or web 30 is held between the first and second fingers, and the pack or web 32 is held between the thumb and first finger of the right hand. The carbon-withdrawal mechanism 19 is pushed with the left hand to the rear of the sub-frame 18, thus stripping the work-sheets or plies 30^a and 32^a of both carbons 31 and 33 and shields 31^a, after which both packs or webs are again drawn forward until the first and second fingers of the operator can guide the leading edge of the pack or web 30 to a position of rest against a stop 39 of the lower leading-edge gage 28. A lever 60 attached to a cam 41, suitably mounted

on the gage 28, is then actuated to depress a spring member 42 which clamps the leading edge of the pack or web 30 in position; the lower leading-edge gage 28 being itself held in position on the guide-bar 27 by 70 means of a thumb-screw 43. The position of the pack or web 30 will now remain fixed while the pack or web 32 is being further withdrawn by the thumb and first finger until it reaches a long leg portion 44 of the 75 upper leading-edge gage 29, which has previously been positioned on the gage-bar 27 and fastened there by a thumb-screw 45.

The position of the packs or webs 30 and 32 will now be substantially as shown in 80 Figure 5 of the drawings, and while the pack or web 30 is being held by the lower leading-edge gage 28, and the pack or web 32 is held against the upper leading-edge gage 29 by the thumb and the first finger of the 85 operator's hand, the platen is again lowered, by oscillating the swing-frame upwardly and backwardly about the shaft 16, to its normal position to re-engage the feed-rolls 24 and 25. The leading edges of both packs or webs 30 and 32 are now released, and it is found that the registration marks, which are printed on the work-sheets or plies of both packs or webs 30 and 32 to indicate what are to be the new leading 90 edges of the packs or webs 30 and 32 when typing matter on the second printed forms of each pack or web, are now opposite the edge of a knife 46, and the finished first forms of both packs or webs 30 and 32 may 95 now be torn off in their proper respective lengths preparatory to commencing another complete operation.

Variations may be resorted to within the scope of the invention, and portions of the 100 improvements may be used without others.

Having thus described my invention, I claim:

1. In a typewriting machine of the fan-fold or continuous billing type, in combination, a revoluble platen, means to guide superimposed packs or webs of work-sheets or plies, having carbon-sheets interleaved therebetween and having forms of different lengths printed thereon, underneath and around said platen, means for protecting said forms printed on said work-sheets or plies of some of said packs or webs from receiving the impression of part, but not all, of the matter typed on other of said forms printed on said work-sheets or plies of other of said packs or webs, means for lifting or displacing said platen to provide for the straightening out and drawing forward of said packs or webs, and means rendered operative only when said platen is lifted or displaced for separately gaging the leading edges of said packs or webs, while in straightened condition, to enable each of said packs or webs to be withdrawn different 110 115 120 125 130

distances from the machine and thus enable said work-sheets or plies to be cut off in different lengths from said packs or webs.

2. In a typewriting machine of the fan-fold or continuous billing type, in combination, a revoluble platen, means to guide superimposed packs or webs of work-sheets or plies, having carbon-sheets interleaved therebetween and having forms of different 10 lengths printed thereon, underneath and around said platen, means for protecting said forms printed on said work-sheets or plies of some of said packs or webs from receiving the impression of part, but not all, of the 15 matter typed on other of said forms printed on said work-sheets or plies of other of said packs or webs, said protecting means comprising pliable shields or blank sheets so disposed in relation to said carbon-sheets 20 interleaved between said work-sheets or plies of said packs or webs as to render part, but not all, of their printing surfaces ineffective, means for lifting or displacing said platen to provide for the straightening 25 out and drawing forward of said packs or webs, and means rendered operative only when said platen is lifted or displaced for separately gaging the leading edges of said 30 packs or webs, while in straightened condition, to enable each of said packs or webs to be withdrawn different distances from the machine, and thus enable said work-sheets or plies to be cut off in different 35 lengths from said packs or webs.
3. In a typewriting machine of the fan-fold or continuous billing type, in combination, a revoluble platen, means to guide superimposed packs or webs of work-sheets or plies, having carbon-sheets interleaved 40 therebetween and having forms of different lengths printed thereon, underneath and around said platen, means for protecting said forms printed on said work-sheets or plies of some of said packs or webs from receiving the impression of part, but not all, of the 45 matter typed on other of said forms printed on said work-sheets or plies of other of said packs or webs, means for withdrawing said carbon-sheets together 50 with said protecting means from between the work-sheets or plies of said packs or webs, said withdrawing means comprising a movable table on which are mounted suitable clamping members for holding said 55 carbon-sheets and said protecting means, means for lifting or displacing said platen to provide for the straightening out and drawing forward of said packs or webs, and means rendered operative only when said 60 platen is lifted or displaced for separately gaging the leading edges of said packs or webs, while in straightened condition, to enable each of said packs or webs to be withdrawn different distances from the 65 machine and thus enable said work-sheets or

plies to be cut off in different lengths from said packs or webs.

4. In a typewriting machine of the fan-fold or continuous billing type, in combination, a revoluble platen, means to guide superimposed packs or webs of work-sheets or plies, having carbon-sheets interleaved therebetween and having forms of different lengths printed thereon, underneath and around said platen, means for lifting or displacing said platen to provide for the straightening out and drawing forward of said packs or webs, means, rendered operative only when said platen is lifted or displaced, for separately gaging the leading edges of said packs or webs, while in straightened condition, to enable each of said packs or webs to be withdrawn different distances from the machine and thus enable said work-sheets or plies to be cut off in different lengths from the packs or webs, such gaging means comprising a gage-carrying bar or guide swingable forwardly and downwardly from an upstanding to a substantially horizontal position, at the time of displacement of said platen, directly over said straightened packs or webs, an adjustable lower leading edge gage slidably mounted on said gage-carrying bar or guide for the purpose of gaging the leading edge of an inner one of said straightened packs or webs, and an adjustable upper leading edge gage slidably mounted on said gage-carrying bar or guide, in a position further away from said platen than that of said lower leading edge gage, for the purpose of gaging the leading edge of an outer one of said straightened packs or webs by the further withdrawal of said straightened outer pack or web beyond the leading edge of said straightened inner pack or web.

5. In a typewriting machine of the fan-fold or continuous billing type, in combination, a revoluble platen, a movable swing frame in which said platen is mounted, means to guide superimposed packs or webs of work-sheets or plies, having carbon-sheets interleaved therebetween and having forms of different lengths printed thereon, underneath and around said platen, a main platen-frame in which said movable swing frame is mounted to swing upwardly and forwardly, and, in so doing, lift or displace said platen to provide for the straightening out and drawing forward of said packs or webs, a gage-carrying bar or guide mounted on said swing frame to move therewith forwardly and downwardly from an upstanding to a substantially horizontal position, at the time of displacement of said platen, directly over said straightened packs or webs, an adjustable lower leading edge gage slidably mounted on said gage-carrying bar or guide for the purpose 125

- of gaging the leading edge of an inner one of said straightened packs or webs, a pack or web gripping device so mounted on said lower leading edge gage as to grip or hold the leading edge of said straightened inner pack or web in position on said lower leading edge gage while an outer straightened pack or web is being drawn beyond said straightened inner pack or web, and an adjustable upper leading edge gage slidably mounted on said gage-carrying bar or guide in a position further away from said platen than that of said lower leading edge gage for the purpose of gaging the leading edge of an outer one of said straightened outer pack or web beyond the leading edge of said straightened inner pack or web.
6. In a typewriting machine of the fan-fold or continuous billing type, in combination, a revolute platen, means to guide a pack or web of work-sheets or plies, underneath and around said platen, means for lifting or displacing said platen to provide for the straightening out and drawing forward of said pack or web, a gage-carrying bar or guide so disposed as to swing forwardly and downwardly from an upstanding to a substantially horizontal position, at the time of displacement of said platen, directly over said straightened pack or web, an adjustable leading edge gage slidably mounted on said gage-carrying bar or guide for the purpose of gaging the leading edge of said straightened pack or web in position on said leading edge gage.
7. In a typewriting machine of the fan-fold or continuous billing type, in combination, a revolute platen, means to guide superimposed packs or webs of work-sheets or plies underneath and around said platen, means for lifting or displacing said platen to provide for the straightening out and drawing forward of said packs or webs, means for separately gaging the leading edges of said packs or webs while in straightened condition, to enable one of said packs or webs to be made up of work-sheets or plies having one length of form printed thereon, and another of said packs or webs to be made up of work-sheets or plies having a different length of form printed thereon, said gaging means comprising a gage-carrying bar or guide, so disposed as to swing forwardly and downwardly from an upstanding to a substantially horizontal position, at the time of displacement of the platen, directly over said straightened packs or webs, an adjustable lower leading edge gage, slidably mounted on said gage-carrying bar or guide for the purpose of gaging the leading edge of an inner one of said straightened packs or webs when said straightened inner pack or web is drawn forward, a pack or web gripping device so mounted on said lower leading edge gage as to grip or hold the leading edge of said straightened inner pack or web in position on said lower leading edge gage while an outer straightened pack or web is being drawn beyond said straightened inner pack or web, an adjustable upper leading edge gage slidably mounted on said gage-carrying bar or guide in a position further away from said platen than that of said lower leading edge gage, for the purpose of gaging the leading edge of an outer one of said straightened packs or webs by further withdrawal of said straightened outer pack or web beyond the leading edge of said straightened inner pack or web, and a web-severing or cutting knife.
- the leading edge of an inner one of said straightened packs or webs when said straightened inner pack or web is drawn forward, an adjustable upper leading edge gage slidably mounted on said gage-carrying bar or guide in a position further away from said platen than that of said lower leading edge gage for the purpose of gaging the leading edge of an outer one of said straightened packs or webs by the further withdrawal of said straightened outer pack or web beyond the leading edge of said straightened inner pack or web, and a web-severing or cutting knife fastened in a fixed position relative to, but movable with, said platen for cutting said packs or webs, at a common registration mark placed thereon, after said packs or webs have been gaged, and after said platen has been returned to its normal position.
8. In a typewriting machine of the fan-fold or continuous billing type, in combination, a revolute platen, means to guide superimposed packs or webs of work-sheets or plies underneath and around said platen, means for lifting or displacing said platen to provide for the straightening out and drawing forward of said packs or webs, means for separately gaging the leading edges of said packs or webs, while in straightened condition, to enable one of said packs or webs to be made up of work-sheets or plies having one length of form printed thereon and another of said packs or webs to be made up of work-sheets or plies having a different length of form printed thereon, said gaging means comprising a gage-carrying bar or guide, so disposed as to swing forwardly and downwardly from an upstanding to a substantially horizontal position, at the time of displacement of the platen, directly over said straightened packs or webs, an adjustable lower leading edge gage, slidably mounted on said gage-carrying bar or guide for the purpose of gaging the leading edge of an inner one of said straightened packs or webs when said straightened inner pack or web is drawn forward, a pack or web gripping device so mounted on said lower leading edge gage as to grip or hold the leading edge of said straightened inner pack or web in position on said lower leading edge gage while an outer straightened pack or web is being drawn beyond said straightened inner pack or web, an adjustable upper leading edge gage slidably mounted on said gage-carrying bar or guide in a position further away from said platen than that of said lower leading edge gage, for the purpose of gaging the leading edge of an outer one of said straightened packs or webs by further withdrawal of said straightened outer pack or web beyond the leading edge of said straightened inner pack or web, and a web-severing or cutting knife.

fastened in a fixed position relative to, but movable with, said platen for cutting said packs or webs at a common registration mark placed thereon after said packs or webs have been gaged, and after said platen has been returned to its normal position.

9. In a typewriting machine of the fan-fold or continuous billing type, in combination, a revoluble platen, a movable swing frame in which said platen is mounted, means to guide superimposed packs or webs of work-sheets or plies underneath and around said platen, a main platen-frame in which said movable swing frame is mounted to swing upwardly and forwardly, and, in so doing, lift or displace said platen to provide for the straightening out and drawing forward of said packs or webs, means for separately gaging the leading edges of said packs or webs while in straightened condition, to enable one of said packs or webs to be made up of work-sheets or plies having one length of form printed thereon, and another of said packs or webs to be made up of work-sheets or plies having a different length of form printed thereon, said gaging means comprising a gage-carrying bar or guide so disposed as to swing forwardly and downwardly from an upstanding to a substantially horizontal position, at the time of displacement of the platen, directly over said straightened packs or webs, an adjustable lower leading edge gage, slidably mounted on said gage-carrying bar or guide for the purpose of gaging the leading edge of an inner one of said straightened packs or webs when said straightened inner pack or web is drawn forward, a pack or web gripping device so mounted on said lower leading edge gage as to grip or hold the leading edge of said straightened inner pack or web in position on said lower leading edge gage, an adjustable upper leading edge gage slidably mounted on said gage-carrying bar or guide in a position further away from said platen than that of said lower leading edge gage, for the purpose of gaging the leading edge of an outer one of said straightened packs or webs by the further withdrawal of said straightened outer pack or web beyond the leading edge of said straightened inner pack or web, an adjustable upper leading edge gage slidably mounted on said gage-carrying bar or guide in a position further away from said platen than that of said lower leading edge gage, for the purpose of gaging the leading edge of an outer one of said straightened packs or webs by the further withdrawal of said straightened outer pack or web beyond the leading edge of said straightened inner pack or web, and a web-severing or cutting knife fastened in a fixed position relative to, but movable with, said platen for cutting said packs or webs at a common registration mark placed thereon after said packs or webs have been gaged and after said platen has been returned to its normal position.

10. In a typewriting machine of the fan-fold or continuous billing type, in combination, a revoluble platen, a movable swing

frame in which said platen is mounted, means to guide superimposed packs or webs of work-sheets or plies, having carbon-sheets interleaved therebetween and having forms of different lengths printed thereon, underneath and around said platen, means for protecting said forms printed on said work-sheets or plies of some of said packs or webs from receiving the impression of part, but not all, of the matter typed on other of said forms printed on said work-sheets or plies of other of said packs or webs, means for withdrawing said carbon-sheets together with said protecting means from between said work-sheets or plies of said packs or webs, a main platen-frame in which said movable swing frame is mounted to swing upwardly and forwardly, and, in so doing, lift or displace said platen to provide for the straightening out and drawing forward of said packs or webs, a gage-carrying bar or guide mounted on said swing frame to move therewith forwardly and downwardly from an upstanding to a substantially horizontal position, at the time of displacement of the platen, directly over said straightened packs or webs, an adjustable lower leading edge gage slidably mounted on said gage-carrying bar or guide for the purpose of gaging the leading edge of an inner one of said straightened packs or webs when said inner pack or web is drawn forward, a pack or web gripping device so mounted on said lower leading edge gage as to grip or hold the leading edge of said straightened inner pack or web in position on said lower leading edge gage, an adjustable upper leading edge gage slidably mounted on said gage-carrying bar or guide in a position further away from said platen than that of said lower leading edge gage, for the purpose of gaging the leading edge of an outer one of said straightened packs or webs by the further withdrawal of said straightened outer pack or web beyond the leading edge of said straightened inner pack or web, and a web-severing or cutting knife fastened in a fixed position relative to, but movable with, said platen for cutting said packs or webs, at a common registration mark placed thereon, after said packs or webs have been gaged and after said platen has been returned to its normal position.

11. In a typewriting machine of the fan-fold or continuous billing type, in combination, a revoluble platen, means to guide superimposed packs or webs of work-sheets or plies, having carbon-sheets interleaved therebetween and having forms of different lengths printed thereon, underneath and around said platen, means for lifting or displacing said platen to provide for the straightening out and drawing forward of said packs or webs, and means rendered operative only when said platen is lifted or

displaced, for separately gaging the leading edges of said packs or webs while in straightened condition, to enable each of said packs or webs to be withdrawn different distances from the machine and thus enable said work-sheets or plies to be cut off in different lengths from said packs or webs, said gaging means comprising a gage-carrying bar swingable forwardly and downwardly from an upstanding to a substantially horizontal position, at the time of displacement of said platen, an adjustable lower leading edge gage slidably mounted on said gage-carrying bar or guide and projecting forwardly therefrom for gaging the leading edge of an inner one of said straightened packs or webs when said inner pack or web is drawn forward, a pack or web gripping device so mounted on said lower leading edge gage as to grip or hold the leading edge of said straightened inner pack or web in position on said lower leading edge gage, and an adjustable upper leading edge gage slidably mounted on said gage-carrying bar or guide in a position further away from said platen than that of said lower leading edge gage and projecting forwardly therefrom for gaging the leading edge of an outer one of said straightened packs or webs by the further withdrawal of said straightened outer pack or web beyond the leading edge of said straightened inner pack or web, said upper leading edge gage projecting further forwardly from said gage-carrying bar or guide than said lower leading edge gage and said gripping device, so that said lower leading edge gage and said gripping device will not interfere with the further withdrawal and gaging of said straightened outer pack or web after said straightened inner pack or web has been gaged by said lower leading edge gage, and gripped by said gripping device.

12. In a typewriting machine, the combination of a carbon-carrier, a displaceable platen, a gage-bar, two gaging members relatively adjustable on said bar, one in advance of the other for gaging at different locations the leading edges of diversified superposed packs of work-sheets, and means on the inner gaging member for clamping the leading edges of the underlying pack while the carbon-carrier retracts manifold sheets, said clamping means and its associated gaging member being covered by the advanced pack.

13. In a typewriting machine, the combination of a displaceable platen, a carbon-carrier, a gage for gaging one pack of work-sheets, a second gage in advance of the first gage and standing higher than the first gage for gaging a second pack of work-sheets superposed upon the first pack and extending to the second gage, and a web-holding clamp upon one of said gages engaging one pack during the retraction of said carbon-carrier.

14. In a typewriting machine, the combination of a displaceable platen including a line-feeding mechanism for feeding a pair of continuous work-sheet-packs having blank forms which are fed around the platen in unison, the inner pack composed of short forms and the outer pack composed of substantially longer forms, carbon-inlays for said packs, a carrier to which all of said carbon-inlays are attached, means for rendering the carbons for the inner pack effective only upon the first set of forms thereon, a gage for each work-pack to gage the leading edge of one pack in staggered relation to the leading edge of the other pack to bring the severing positions of both packs into alignment, and means to sever both packs in unison at the single severing position determined by the gages.
